US0D1098934S

(12) **United States Design Patent** (10) **Patent No.:** **US D1,098,934 S**
(45) **Date of Patent:** **** Oct. 21, 2025**

(54) **DEVICE FOR MEASURING PARTICLES**

(71) Applicant: **DONGWOO FINE-CHEM CO., LTD.**, Jeollabuk-do (KR)

(72) Inventors: **Gi Hwan Ahn**, Jeollabuk-do (KR); **Sung Ho Baek**, Jeollabuk-do (KR); **Woo Hwan Sul**, Jeollabuk-do (KR); **Min Ju Lee**, Jeollabuk-do (KR); **Seung Pil Han**, Jeollabuk-do (KR)

(73) Assignee: **DONGWOO FINE-CHEM CO., LTD.**, Jeollabuk-Do (KR)

(**) Term: **15 Years**

(21) Appl. No.: **29/905,349**

(22) Filed: **Oct. 19, 2023**

(57) **CLAIM**

The ornamental design for a device for measuring particles, as shown and described herein.

DESCRIPTION

FIG. 1 is a perspective view of the device for measuring particles of the present invention;

FIG. 2 is a front view thereof;

FIG. 3 is a rear view thereof;

FIG. 4 is a left side view thereof;

FIG. 5 is a right side view thereof;

FIG. 6 is top view thereof;

FIG. 7 is a bottom view thereof; and,

FIG. 8 is a perspective view of the device for measuring particles of the present invention, at a different angle.

The broken lines in the figures depict portions of the device for measuring particles which form no part of the claimed design.
